UNITED STATES PATENT OFFICE.

THOMAS C. OCTIGAN, OF CHICAGO, ILLINOIS.

COMBINED HORSESHOE AND PAD.

No. 807,045.

Specification of Letters Patent.

Patented Dec. 12, 1905.

Application filed June 15, 1903. Serial No. 161,471.

To all whom it may concern:

Be it known that I, THOMAS C. OCTIGAN, of Chicago, in the county of Cook and State of Illinois, have invented certain new and useful 5 Improvements in a Combined Horseshoe and Pad; and I do hereby declare that the following is a full, clear, and exact description thereof, reference being had to the accompanying drawings, and to the letters of reference 10 marked thereon, which form a part of this specification.

This invention relates to an improved combined horseshoe and pad and also to a novel tip or three-quarter shoe adapted for use in 15 connection with such pads.

The invention consists in the matters hereinafter set forth, and more particularly pointed out in the appended claims.

In the drawings, Figure 1 is a bottom plan 20 view of a combined horseshoe and pad made in accordance with my invention. Figs. 2 and 3 are sections taken on lines 2 2 and 3 3, respectively, of Fig. 1. Fig. 4 is a perspective view of the tip or three-quarter shoe removed 25 from the pad. Fig. 5 is a fragmentary view showing a modification of the tip.

As shown in the drawings, A designates a three-quarter or tip shoe, and B designates as a whole the pad. Said pad consists of a base B', 30 made of leather or like material, and a yielding or cushioning part made of rubber. Said base is made of exterior dimensions and shape to fit the foot of the animal to which the combined shoe and pad is to be applied. The 35 cushioning part of the pad consists of a web portion B², which fits flat against the base B', a thickened wide transverse bar portion B³ at the rear end of the pad, and a curved rim B⁴, which surrounds the central part of the web 40 and is joined at its rear ends to said bar portion and conforms generally to the curvature of the margin of the base B'. The arrangement of said rim thus forms centrally of the pad a deep downwardly-opening recess. Said 45 yielding or cushioning part of the pad is provided around the rim B⁴ with a radial flat flange b and in rear of the transverse bar portion B³ with a rearwardly-directed flange b', and it is attached to the leather base by means 50 of stitches extending through said flanges b b' and through said base in the manner shown in Figs. 1, 2, and 3. The offset outside of the margin of the yielding portion of the pad B and between the same and the flange b constitutes a curved marginal rabbet of angular 55 cross-section which receives the tip A.

The shoe or tip A (shown best in Fig. 4) consists of a curved flat web A' and a flange A², located at the inner margin of said web and closely embracing the rim B⁴ of the pad 60 when the parts are assembled. Said flange A² constitutes a continuous calk which is co-extensive with the shoe, and it is preferably thickened to provide at the front of the shoe a toe-calk A³. Said flange or calk A², which 65 is made thin and of substantially equal thickness throughout its length, may also be thickened at the rear ends thereof to provide laterally-directed calks A⁴, as shown in Fig. 5. The continuous curved flange serves to hold 70 the shoe from slipping in all directions, and the lateral calk A⁴ (shown in Fig. 5) and toe-calk serve as an additional safeguard to prevent the shoe from slipping forwardly and backwardly. The web is provided with nail-holes a, through which the holding-nails are 75 adapted to extend, said holding-nails also extending through the pad and fastening the same between the shoe and hoof in a familiar manner.

The continuous calk-flange A², which closely embraces the rim B⁴ of the pad, serves to support and protect the rim from being broken during use by sharp stones and uneven surfaces on the roadway. The location of said 80 flange at the inner margin of the web, and therefore inside of the line of nail-holes, is of considerable importance not only for the reason mentioned, but because it permits free access to the nails when the latter are 85 driven into or withdrawn from the hoof and does not interfere with the driving of the nails at the proper angle into the hoof. The yielding or cushioning portion of the pad extends but slightly below the flange A² of 90 the shoe, and the rim of said cushioning part is preferably made hollow, as shown in Figs. 2 and 3. Said rim therefore yields or recedes after the first impact of the shoe on 95 the roadway, so as to bring the weight upon 100 the flange or calk A² of the shoe or tip, thereby avoiding excessive wear upon said cushioning part of the pad and conserving the life of the pad. The rim therefore serves as a cushion to break the force of the impact of the shoe 105 upon the roadway and to avoid slipping when the shoe first strikes the roadway, while the continuous flange or calk is at hand to receive the full weight of the animal, and its form and arrangement are such that it prevents the 110 shoe slipping when the full weight of the animal is brought upon the shoe. The flange

is made thin and may be so made and possess ample strength by reason of its continuity, and does not, therefore, become dulled when it wears away, but by reason of its substantial uniform thickness retains throughout its service the edge of a newly-sharpened shoe. It has been a common practice heretofore to make shoes or tips of this character of considerable width for contact with the roadway, and after a short period of wear they become smooth on their lower or contact faces and lose their holding efficiency. To overcome such objection, it has been common to extend the cushioning part of the pad used therewith a considerable distance beyond or below the shoe, so as to rely for the holding effect principally upon the cushion. Such holding action of the cushion, unassisted by the rim, results in a short life of the effective holding function of the pad, and when the parts are worn so as to bring the shoe proper in contact with the roadway the latter soon wears smooth, as before stated. In my construction the rim need not be made to extend far beyond the pad, which extension is objectionable; but the rim takes hold of the roadway at the same time as the pad, thereby giving the desired yielding and holding quality to the combined shoe and pad. Another important advantage of the form of tip or shoe herein shown is that it may be made very light and yet amply strong and possess the holding qualities necessary in a successful shoe. The calk, adding but little weight to the shoe, may be made as deep as desired.

The provision of the lateral calks A⁴ is of considerable importance, as it strengthens the rear ends of the shoe and considerably delays the wearing away of the calk-flange A² and increases the life thereof.

In some instances the toe-calk A³ may be recessed, as shown in Figs. 1, 2, and 4, to pro-

vide, in effect, a double calk, each being made sufficiently sharp to afford a reliable hold of the calk on the roadway.

45

I claim as my invention—

1. A combined horseshoe and pad comprising a pad provided on its under surface at its outer margin with a curved rabbet of angular cross-section and a three-quarter or tip shoe 50 located in said rabbet and comprising a flat web provided with nail-holes and a continuous calk-flange extending from one end of the shoe to the other, said flange being located at the inner margin of said web and closely 55 embracing the pad.

2. A combined horseshoe and pad comprising a pad consisting of a continuous base made of tough, durable material, a flat web which fits against said base, a transverse bar portion at the rear thereof and a forwardly-extending rim inclosing the central part of the web, said rim being located inside the margin of said base, and a three-quarter shoe or tip 60 surrounding said rim and comprising a flat 65 horizontal web provided on its inner margin in contact with said rim with a continuous calk or flange coextensive with the web.

3. A combined horseshoe and pad comprising a pad having on its under surface a rim 70 surrounding a central recess, of a three-quarter or tip shoe comprising a flat web and a thin vertical flange of substantially equal thickness throughout its height and coextensive with the web and closely embracing said 75 rim.

In testimony that I claim the foregoing as my invention I affix my signature, in presence of two witnesses, this 11th day of June, A. D. 1903.

THOMAS C. OCTIGAN.
